UNITED STATES PATENT OFFICE

JULIUS HERRIET, OF NEW YORK, N. Y., ASSIGNOR TO DAVID WOLFE BRUCE,
OF SAME PLACE.

DESIGN FOR FONT OF PRINTING-TYPES.

Specification forming part of Design No. 7,995, dated January 12, 1875; application filed December 8, 1874.
[Term of Patent 14 years.]

To all whom it may concern:

Be it known that I, JULIUS HERRIET, of the city, county, and State of New York, have originated and designed a new Pattern for Printing-Types, which I describe as follows:

The nature of my design is clearly shown in the accompanying typographic impression, to which reference is made, and which differs from every other kind of type in style and proportion. It consists of ornamented lower-case, points, figures, and capitals, surrounded by a hair-line, with a white spot on the inside

of the bowls of the circular characters, and the capitals ornamented with tendrils to fill up the counters.

What I claim as my invention, and desire to secure by Letters Patent, is—

The design or pattern for a font of printing-types, herein shown and described.

JULIUS HERRIET.
